BROACHING MACHINE

Oliver W. Bonnaffon, Hudson, Mass., assignor to
The Lapointe Machine Tool Company, Hudson,
Mass., a corporation of Maine

Application February 11, 1946, Serial No. 646,907

3 Claims. (Cl. 90—3)

1

This invention relates to a broaching machine capable of general application but particularly designed for broaching involute teeth on circular gear blanks.

It is the general object of my invention to provide a broaching machine by which involute spur gears may be accurately and automatically produced in reduced time and at substantially less expense than has heretofore prevailed.

To the attainment of this general object, I provide a machine in which a sectional broach is given a continuous straight-line vertical travel axially of the gear blanks, and in which the gear blanks roll in a horizontal plane transversely across the cutting face of the continuously moving sectional broach.

I also provide means to positively advance each broach section through the cutting locus, means to positively advance each gear blank through the cutting locus, and means to positively rotate the gear blank at a speed accurately corresponding to its rolling pitch line.

My invention further relates to arrangements and combinations of parts which will be herein-after described and more particularly pointed out in the appended claims.

A preferred form of the invention is shown in the drawings, in which

Fig. 1 is a partial side elevation of my improved broaching machine, with parts of the casing shown indicated diagrammatically only;

Fig. 2 is a sectional plan view, taken substantially along the line 2—2 in Fig. 1;

Fig. 3 is an enlarged sectional side elevation of certain work-supporting and work-feeding structure;

Fig. 4 is a rear elevation of a portion of the sectional broach;

Fig. 5 is a front elevation of one broach section;

Fig. 6 is a side elevation, looking in the direction of the arrow 6 in Fig. 5;

Fig. 7 is an enlarged partial plan view of a broach section and associated guideway, partly in section;

Fig. 8 is a partial side elevation of a modified broach section guide; and

Fig. 9 is a partial front elevation of certain work table adjusting mechanism, looking in the direction of the arrow 9 in Fig. 2.

Referring to the drawings, my improved broaching machine may be described as comprising broadly a broach-supporting and driving mechanism A and a work-supporting and driving mechanism B.

2

The mechanism A comprises a casing 10 having bearings for an upper cross shaft 11 and a lower cross shaft 12, each having a pair of sprockets or guide discs 14 on which a sectional broach is supported. The shafts 11 and 12 are freely rotatable and the sprockets 14 have no driving function.

The sectional broach comprises broach sections shown in detail in Figs. 4, 5 and 6 and each comprising a front plate 20 having parallel vertical rows 21 of broaching teeth on its front face. Each front plate 20 is mounted on a back plate 22 having upper ears 23 and lower ears 24, pivotally connected by cross rods 25 which may be held from endwise displacement by screws 26. The ends of the rods 25 are received in suitably spaced notches in the periphery of the guiding sprockets or discs 14 (Fig. 1).

The width of the front plate 20 is such that the number of rows 21 of broaching teeth exceeds the number of teeth in the gear to be broached, so that the gear blank will perform slightly more than a complete revolution in rolling across the cutting face of the sectional broach. The ends 25 of the plate 20 are grooved or recessed as shown in Fig. 7, and have a close sliding fit on fixed vertically extending guideways 29.

Each broach section is provided on its rear face with rack plates 30 and 31 (Fig. 4) having helical rack teeth disposed at reversed angles to neutralize end thrust. These rack teeth are engaged by helical gears 33 and 34 (Fig. 2) mounted on a shaft 35 rotatable in fixed bearings 36 and 37 and provided with a worm gear 38. The gear 38 is driven by a worm 40 (Fig. 1) mounted on a shaft 41 which is driven from a motor M through a plurality of belts 42, or which may be continuously rotated from any other convenient source of power.

With the driving mechanism above described, it will be seen that the helical gears 33 and 34 are continuously and positively rotated and that they engage the rack plates 30 and 31 on the broaching sections as each section passes through the broaching locus and that they positively advance each broach section as it performs its broaching operation. There is thus a direct application of power at the cutting point, and all lost motion, irregularity or chatter is effectively avoided.

As previously stated, the guiding sprockets or discs 14 have no driving function and these discs may be replaced by fixed circular guideways 44 as shown in Fig. 8.

55 The mechanism B for supporting and driving

the gear-blanks or other pieces of work comprises a pair of sprockets 60 (Figs. 2 and 3) loosely mounted on pivot studs 61 fixed in the frame 62 of the work table 63. Studs 64 in work-supporting blocks 65 are received in the notches of the sprockets 60, and adjacent blocks 65 are connected by links 66 as best shown in Fig. 2.

A gear 67 (Fig. 3) on a stud 68 is rotatably mounted in each block 65, and these gears 67 continuously engage a rack plate 69 which extends entirely around the work table 63 and which is semi-circular in its end portions and straight along its side portions. Each gear 67 and stud 68 is connected by gears 70 and 71 to rotate a stud 72, also mounted in the block 65.

Each stud 72 has provision for receiving a gear blank K and preventing relative rotation thereof on the stud. The gears 70 and 71 are preferably of equal size, and the pitch line of the gear 67 is preferably of the same diameter as the pitch-line of the gear to be cut from the blank K.

Each work-supporting block 65 has a segmental nut 74 which engages a lead screw 75 mounted on a shaft 76 extending parallel to the front face of the operatively-positioned broach section. The shaft 76 may be driven through gears 77 and 78 (Fig. 1) from a shaft 79 connected by belts 80 to a shaft 81 which is continuously rotated by a suitable motor or other source of power, not shown.

All of the work-supporting parts thus far described are mounted on the work table 63 (Fig. 3), which is supported in suitable guideways 90 (Fig. 9) on a base 91 and which has a half nut 92 (Fig. 3) engaging an adjusting screw 93. The screw 93 is formed on a shaft 94 mounted in bearings on the base 91 and rotatable by a hand wheel 95 through reduction gears 96 and 97. By turning the hand wheel 95, the work table 63 and gear blanks K may be adjusted forward or rearward relative to the sectional broach to bring the pitch-line of the gear to be produced into alignment with the pitch-line of the broach.

The entire system of work-supporting blocks 65 is continuously advanced by engagement of the lead screw 75 with one or more of the segmental nuts 74 on the blocks 65 which are moving through the broaching locus. As each block is thus positively advanced, the gear 67 in said block is positively rotated by its engagement with the fixed rack plate 69. The diameter of the gear 67 is so related to the diameter of the gear blank K that the pitch-line of the gear blank will roll past the sectional broach at the same speed that the gear 67 rolls past the fixed rack plate 69. The gear blank K is thus positively rotated and at the same time is positively advanced past the sectional broach, and the sectional broach is continuously moved downward, thereby correctly developing and cutting involute teeth on the gear blank.

As has been previously stated, the width of the cutting face of each broach section is somewhat greater than the circumference of the gear blank, so that the blank will make something more than a complete revolution in passing across the cutting locus of the sectional broach. Thus a com-

plete gear will be produced by a single passage of the blank across the sectional broach.

Although the chain of work-supporting blocks 65 moves continuously, the movement is not so rapid as to prevent removal of finished gears and insertion of new blanks during the passage of the blocks along the front of the machine.

Such a machine has been found highly productive and in one illustrative application thereof, finished gears were produced at the rate of six per minute, which is about as fast as a single operator can remove the finished gears and replace them with new gear blanks.

It will be understood that the gears 67 may be varied in size to correspond to the pitch diameter of the desired gears to be produced, and that the rack plate 69 will be positioned to engage the particular gears 67 in use for a certain operation.

Having thus described my invention and the advantages thereof, I do not wish to be limited to the details herein disclosed, otherwise than as set forth in the claims, but what I claim is:

1. In a machine for broaching gears, a broaching apparatus comprising separate successive broaching sections connected together, means to support said broaching apparatus for feeding movement, gear means directly engaging each broach section so long as it is in the broaching area and positively and continuously advancing said section through said broaching area, means to move a gear blank positively and continuously through said broaching area in engagement with said broaching apparatus and in a plane perpendicular to the plane of operation of said apparatus, and means to positively rotate said gear blank as it is moved through said broaching area.

2. In a broaching machine, a broach formed of a plurality of separate sections connected together and movable in a closed path into, through and out of a broaching area, and a positive gear drive directly engaging and driving each successive section so long as it is in said broaching area.

3. In a broaching machine, a broach formed of a plurality of separate sections connected together and movable in a closed path into, through and out of a broaching area, each broach section having reversed helical rack plates on the back thereof, reversed helical gears located in said broaching area and continuously engaging said rack plates so long as each broach section is in the broaching area, and means to positively rotate said helical gears.

OLIVER W. BONNAFE.
